UNITED STATES PATENT OFFICE

FREDERICK J. CROSS AND HOWARD H. SCHOTT, OF ROCHESTER, NEW YORK, ASSIGNORS
TO ROBESON-ROCHESTER CORPORATION, OF ROCHESTER, NEW YORK, A CORPORA-TION OF NEW YORK

DESIGN FOR A WAFFLE IRON

Application filed July 22, 1929. Serial No. 32,166. Term of patent 3½ years.

To all whom it may concern:

Be it known that we, FREDERICK J. CROSS and HOWARD H. SCHOTT, both citizens of the United States, residing at Rochester, in the county of Monroe and State of New York, have invented a new, original, and ornamental Design for Waffle Iron, of which the following is a specification, reference being had to the accompanying drawing, forming part thereof.

Fig. 1 is a top plan view, and Fig. 2 is a side elevation of a waffle iron, showing our new design.

We claim:

The ornamental design for a waffle iron, substantially as shown.

FREDERICK J. CROSS.
HOWARD H. SCHOTT.
